CLAIM

The ornamental design for a nozzle for a fire fighting tool, as shown and described.

DESCRIPTION

FIG. 1 is a side elevational view of a new design for a nozzle for a fire fighting tool, the opposite side being the same as the side down;

FIG. 2 is a left side elevational view and shown rotated 180 degrees from FIG. 1;

FIG. 3 is a right side elevational view and shown rotated 180 degrees from FIG. 1;

FIG. 4 is a front end view thereof; and,

FIG. 5 is a rear end view thereof.

FIG. 1

FIG. 2

FIG. 3

FIG. 5

FIG. 4
